Machines Corporation, New York, N. Y., a cor-
poration of New York

Application December 16, 1930, Serial No. 502,731
In Austria December 18, 1929

14 Claims. (Cl. 101—93)

This invention relates to machines capable of making a duplicate of the statements appearing on members, such as for example, tabulating cards, on a paper-strip by means of a printing or copying process. The invention consists in the provision of selective devices for printing, according to requirements, only the statements appearing at certain places on the cards. Further, according to the invention, arrangements are provided for printing, according to choice, the contents of the cards on different tabular strips. In view of the results effected by the present invention machines capable of effecting these results are especially adapted for bookkeeping and statistical purposes, because the statements appearing on the cards can be distributed and transferred to different tabular strips according to predetermined requirements, for instance according to different data on accounts.

A preferred construction of the invention is illustrated in the accompanying drawings, the transferring or printing device being combined in such a manner with a machine controlled by perforated cards, that the perforated cards, which control the said machine, also contain statements which are transferred to a strip by an arrangement, operating on the principle of metallography.

Figs. 1 and 8 are examples of cards having written matter to be transferred. Fig. 2 is a view in elevation of the essential elements of the machine for transferring statements on cards to a strip and of the devices for analyzing perforated cards, Fig. 3 is a plan view of the parts shown in Fig. 2, and Fig. 4 is a detail view. Figs. 5 and 6 show a counter of the machine which is controlled by perforated cards. Fig. 7 is a view of a tabular strip, while Fig. 9 is a modified construction of the machine.

The card shown in Fig. 1 is provided with perforations and printed characters, and the card controlled machine may have provisions for adding the numbers represented by the perforations and at the same time produce a tabular-strip which may be of the form shown in Fig. 7. The written statements, which have to be transferred and which in the illustrated embodiments are shown above the dash-dot line on the card shown in Fig. 1 and for instance, typed by a typewriter. The text is copied on the backside of the tabulating card in reversed writing and in known manner by means of a hectographic carbon paper disposed behind the card.

As shown, the data on the card relates to a

bank-draft, while the tabular strip shows, for instance, the booking sheet for transfers.

The card is operated on by the machine in the following manner:—The card is placed in the receptacle 1 (Fig. 2) of the machine together with other cards, which have to be treated in the same way. A reciprocating card picker 2 removes the cards singly from the receptacle and feeds them to continuously rotating feed-rollers 3, which feed the cards to the feeler-mechanism 4. 10 As they pass, the feelers through perforations in the card, close in known manner a current-circuit and consequently excite a magnet 103, (Fig. 5) which is arranged in a corresponding counter 5 (Fig. 2) and attracts its armature 110, thereby 15 turning the figure-wheel 116 a unit by means of a pawl 111. The figure-wheel is turned a number of steps commensurate with the number of the perforations successively arranged in a vertical row of the card and corresponding to the numerical value of the represented number. Obviously, a feeler is provided for each row of perforations of the card and a counter 5 for a plurality of rows of holes representing a number.

During its further movement, the card passes 25 between two rollers 6 and 7. The roller 7 co-operates with a roller 8, which rotates in a liquid-filled tank 9. In this way the bottom side of the card, containing the statements to be transferred by hectographic ink, is moistened. Thereafter 30 the card moves between two rollers 10 and 11, which are normally separated from each other, the shaft of the roller 10 (Fig. 4) being forced up in the slot 13 by a spring 12 to such an extent, that the roller 11, which also is forced up by a 35 spring 15, cannot engage the roller 10 in view of the fact that the slot 14 is so proportioned that it will not permit a normal engagement.

Whenever the portion of the card provided with the statements to be transferred is disposed between the rollers 10 and 11, a cam-shaped disc 16, which is attached to a shaft 16' and operated in synchronism with the feed of the card, forces the roller 10 to engage roller 11 and thus the moistened part of the card contacts with a paper- 45 strip 17, which passes over an incline 19 and over said roller 11, whereby the text is transferred from the backside of the card to the paper or tabular strip 17. In view of the further movement of the card, the roller 11 will now be ro- 50 tated from its idle position until the cam-shaped disc 16 again releases the roller 10 so that it is disengaged from roller 11, this event taking place after the desired text is transferred to strip 17. Thus an additional feeding device is not neces- 55

sary for feeding the paper-strip 17 to separate the printed statements on the paper strip 17.

The total of the individual columns can be visually inspected through the windows 18 (Fig. 5 2) of the counters which is usually done after a certain number of cards has been tabulated and the tabular strip completed. The paper-strip 17 preferably passes over an incline 19 and is accessible to the operator so that the total read from 10 the counter can be conveniently written down by the operator at the end of the tabular strip.

In both cases the initial position of the cam disk 16 on its drive shaft 16' with respect to the feeding roller 3 determines on which horizontal 15 line of the card section the transfer will begin.

The height of the transferred strip or the width bounded by imaginary horizontal lines depends upon the effective portion of the cam 16. The cam-shaped disks 16 may be adjustable or interchangeable with another so that the height of the strip to be transferred can be varied according to a predetermined requirement. Obviously the disk 16 may be provided with a number of cams and in this event a number of horizontal strips 25 can be transferred to the strips from the card sections.

The length of the roller 10 can be varied in order to be effective to transfer to the strip only the matter within a section bounded by vertical 30 lines of the card shown in Fig. 1. The arrangement may be such, that the length of the roller 10 corresponds to the vertical width of the statement on the card. Furthermore the roller 10 may be laterally adjustable, so that the same presses 35 onto the roller 11 when a certain part of the card engages the strip 17. Further the roller 10 may be sub-divided, so that a number of vertical portions are printed from the card-section. Thus by the above arrangements any printed part of the card- 40 section can be transferred to the strip by merely varying the two members, namely the cam-shaped disc 16 and the roller 10.

Fig. 9 shows a further construction of the invention. To effect the engagement of each individual roller 10^a, 10^b and 10^c with the related roller beneath there is provided a series of cam-shaped discs 16^a, 16^b and 16^c, to effect the transfer on the associated one of three paper-strips 17^a, 17^b and 17^c which are provided in place of a single 45 paper-strip. Each cam-shaped disc can be coupled with the shaft 27 for rotation by means of a related magnet 25^a, 25^b, 25^c through a coupling 26^a, 26^b, 26^c. Three feelers 28^a, 28^b, 28^c control the 50 selective energization of magnets 25^a, 25^b, 25^c, so that one of the three couplings is operative when the card, analyzed, is found to have perforations 55 in the row controlled by the corresponding feeler 28.

When a perforation is located by a feeler 28, 60 the associated magnet is energized and couples the cam-shaped disc with the drive shaft 27 for operation to the extent of one revolution, so that all statements appearing on the card, determined by the effective portion of the cam and the width 65 of the roller, are transferred to the corresponding tabular strip.

Any desired combination for effecting a transfer between the card and the paper strips can be effected.

The utility of the arrangement disclosed in 70 Fig. 9 will be better understood from the following statements. In the arrangement disclosed in Fig. 9 only three transfer printing strips are disclosed, but in order that this arrangement be 75 useful in connection with the record card dis-

closed in Fig. 8 it will be understood that six strips 17 are employed. From Fig. 8 it will be obvious that the card contains data relating to a bank account entry which is a deposit in the form of cash, check, and bill and the card may be used for making different statements by a single operation of the machine. The first three strips 17^a, 17^b and 17^c, would be correlated with the fields of the record designating cash, check and bill and such strips would receive a reproduction 10 of the printed matter contained in each of these three fields. To the right of the strip 17^c there would be an additional strip on which is im- 15 printed the data of the field d and which data comprises the sum of the amounts in the fields a, b, and c. The two strips which are each as wide as the record card are not shown in Fig. 9 but they would be so positioned to receive the card after issuing from the smaller strips to receive a reproduction of all the printed matter 20 of the four fields and fields e and f of the record card disclosed in Fig. 8. The printed sections of these two wide strips are torn off from the rest of the roll or strip and may be sent to the depositor, and the party in whose name the account is placed, so as to act as an acknowledgement 25 of the deposit.

Obviously other arrangements, for example, mechanical operated devices, may be substituted for the electrical arrangements above described 30 and disclosed in the drawings. Furthermore, the controlling cards may be provided with other forms of designations instead of being perforated to control certain devices in the machine. The invention is not restricted to any particular form 35 of the tabular strip or material thereof and any other equivalent elements may be readily substituted.

I claim:—

1. The combination with a tabulating machine 40 controlled by perforated record cards containing transferable written matter, of feeding means for causing said record to contact with a paper strip, and a cam device operable synchronously with the feeding means for determining the portion of the written matter to contact with the paper strip.

2. In a machine for transferring written matter on perforated records to a paper strip, the combination with means for feeding a record 50 over the paper strip and between a pair of rollers, means for causing said rollers to contact with each other to effect a predetermined area of contact between the record with the paper strip, and means for predetermining the area of contact. 55

3. In a machine for transferring matter written on a perforated card to a paper strip, of means for feeding a card over the paper strip, a pair of rollers for effecting the transfer, and means for shifting one of said rollers to engage the card 60 with the strip for a predetermined feeding movement of the card.

4. In a machine for transferring matter written on a perforated card to a paper strip, means for feeding a card over the paper strip, and means comprising a cam device for causing the card during its movement to contact the strip when portions of the card not containing perforations but containing written matter are in cooperation 65 with the strip.

5. In a machine for transferring written matter on a perforated card to a series of paper strips, means to transfer the written matter to the selected strip, and means controlled solely by the card for causing the matter written upon the 75

card to be transferred by the transfer means to the related paper strip.

6. In a machine of the class described, the combination with a record containing transferrable written matter disposed in sections and of different classification, of a plurality of record strips, means for feeding the record over the series of record strips, and means for selectively causing a physical contact between the strips and the record sections whereby the written matter in the record is transferred to the related record strip.

7. A machine of the class described having in combination, a tabulating card containing perforations and written data, a plurality of record strips each adapted to receive part of the written matter on the tabulating card, and means controlled by the perforations for selectively associating the record strips with the various written data on the card whereby each strip receives the appropriate written data.

8. In a machine controlled by cards containing characters in one area, means for presenting the record cards for contact with a paper strip, a rotatable means for determining the extent of the portion of the area containing the characters on the card that is utilized to transfer such characters to the strip, and electrical means controlled by the cards for controlling the rotatable means.

9. In a machine for transferring to a paper strip data on one section of a card having perforations in another section, means for feeding said card over the paper strip, one section after a section of another kind, means for effecting the transfer of data, and means for preventing a data transfer operation between the paper strip and the perforated section of the card.

10. In a machine for transferring transferable data from one strip to another strip, a mechanism including means for applying an ink dissolving liquid to ink imprints on one of said strips, means for moving said strips while in physical contact with each other to effect the transfer, and means for determining whether certain data on a strip is to be transferred to the other strip.

45 11. In a machine for transferring transferable data from one strip to another strip, a printing

mechanism including means for applying an ink dissolving liquid to ink imprints on one of said strips, means for feeding both strips in contiguous relationship to effect the transfer operation, and means operable synchronously with the feeding means for preventing the transfer operation for a certain section of the strip bearing the transferable data.

5 12. In a machine of the class described, in combination, means for feeding in succession a series of tabulating cards containing ink imprinted transferable data, a printing mechanism including means for applying an ink dissolving liquid to the ink imprints on the tabulating cards for transferring the data from one of the series of cards to a common record strip, means for selecting the data sections on the tabulating card to be transferred to the record strip, and means for feeding the card and strip together for spacing the data on the record strip and for effecting the transfer.

10 13. In a machine of the class described, in combination, means for feeding a record card having a transferable data section, a printing mechanism including means for applying an ink dissolving liquid to ink imprinted characters comprising the data section, for effecting the transfer of the data to a record strip, and means effective during the feeding of the record card for effecting a contiguous relationship between the record card and record strip to effect the transfer and to feed the record strip an extent equivalent to the length of the data section which is utilized for the transfer operation.

15 14. In a machine for transferring written matter on a perforated record to a paper strip, the combination of a transfer means for transferring the written matter on the record to the paper strip and effective when the paper strip and card are fed with the written matter of the card in contact with the paper strip, and means for preventing a transfer operation between the paper strip and the perforated record when both the perforations and an undesired written portion of the record are adjacent the paper strip.

20 25 30 35 40 45 GUSTAV TAUSCHEK.
